MACHINE FOR GRINDING GEARS

Frederick A. Ward, Detroit, Mich., assignor to
The Gear Grinding Machine Company, Detroit,
Mich., a corporation of Michigan

Application December 29, 1930, Serial No. 505,378

5 Claims. (Cl. 51—95)

The invention relates to machines for grinding gears having helical or otherwise curved teeth, being more particularly adapted for grinding helical spur gears and worms. It is the primary object 5 of the invention to accomplish this result by the use of a formed grinder wheel. It is a further object to obtain a construction which will insure a high degree of accuracy, first, as to the contour of each individual tooth surface; second, in indexing from one tooth to another and third, in the form and angle of the helical curve. Still further it is an object to provide for quickly adjusting the machine for the performance of work differing in specific form. With these and other objects 15 in view the invention consists in the construction as hereinafter set forth.

In the drawings:

Figure 1 is a side elevation of the machine;

Figure 2 is a top plan view thereof;

20 Figure 3 is a longitudinal section partly in elevation in the vertical plane of the axis of the work;

Figure 4 is a cross section on line 4—4 of Figure 3;

25 Figure 5 is a cross section on line 5—5 of Figure 3;

Figure 5A is a sectional elevation of the parts shown in Figure 5 viewed from the opposite side;

Figure 6 is a cross section on line 6—6 of Figure 3;

30 Figure 7 is an elevation of one of the exchangeable patterns;

Figure 8 is a diagrammatic perspective view showing the general arrangement of the hydraulic system;

35 Figure 9 is an enlarged horizontal section through a portion of the valve controlling mechanism;

Figure 10 is a vertical section therethrough;

40 Figure 11 is a sectional elevation showing a modified construction.

Broadly described, my improved machine comprises a frame having a formed grinder wheel mounted thereon, a work holder mounted for adjustment into a predetermined angular relation 45 to said grinder wheel, and means for simultaneously imparting to said work holder an axial and a rotative movement such as to maintain the formed cross section of the grinder in the same relation to each portion of the tooth surface 50 successively ground thereby. The machine is further provided with an index mechanism for advancing successive teeth into operative relation to the grinder wheel and a trimmer mechanism through which the correct cross sectional contour 55 of the grinder is restored from time to time.

In detail, A is the bed or frame of the machine; B is a carriage mounted for reciprocation upon said bed and upon which the work is mounted; C is a column extending upward from the bed and D is the grinder wheel which is mounted for vertical adjustment upon the column C. E is a trimming mechanism mounted upon the carriage B so that it can be periodically carried thereby into operative relation to the grinder wheel to retrim the same to the desired contour. The parts thus far described are the same in construction as in many machines heretofore used, and are not an essential part of the present invention.

60 Mounted upon the carriage B is a segmental horizontal base plate F for an angularly adjustable work supporting frame G. The frame G is pivoted to the plate F by a pin G' having a vertical axis which in the normal position of the parts extends upward through the center of the grinder wheel D perpendicularly to and intersecting the axis thereof. The frame G is adjustably secured to the plate F in different positions by suitable means such as the clamping bolts G² passing through slots G³ therein and engaging threaded apertures F' in the plate F. A series of these apertures F' is arranged so that the frame G may be swung about the pin G' through the maximum angle required for variations in the spiral pitch of the gears to be ground. It is, however, desirable to limit the angular adjustment of any particular machine so that the actuating mechanism, which will hereinafter be explained, lies outside of the angle of friction.

65 The frame G has mounted thereon the axially aligned bearings K H' for a rotary and axially movable cylindrical work holder I. The forward end of this work holder I has a socket I' for receiving the work which as specifically shown is a spiral spur gear wheel I³ having a shank or shaft I⁴ engaging the socket. The rear end of the work holder I has a portion I⁵ reduced in diameter forming a mounting for exchangeable pattern sleeves J. Each of these sleeves J is formed with one or more helical grooves J' therein, preferably three of such grooves arranged at equal angles to each other around the periphery of the sleeve. The helical grooves are engaged by pin bearings K which are mounted in a sleeve K' surrounding the members I and J and intermediate the same and the bearing H. The pins K are wedge shaped to fit a corresponding tapered cross section in the helical groove J' and springs K² force these pins radially inward so as to automatically take up any lost motion. Thus assuming that the sleeve K' is held stationary and 70

an axial movement is imparted to the work holder I, this will cause a simultaneous rotation of said member and if the pitch of the helical groove in the pattern sleeve J is the same as the pitch of the helical teeth of the work, the grinder wheel will perform a generating movement over the tooth surfaces to be ground.

For imparting the axial movement to the member I a hydraulic cylinder L is arranged in axial alignment therewith, being supported upon a bracket L' projecting rearward from the frame G. In this cylinder is a piston L² provided with a piston rod L³ connected to the rear end of the member I by the swivel coupling L⁴ which permits independent rotation of said member L. The exchangeable sleeve J is adjustably coupled for rotation with the member I through the medium of a member M clamped to the rear end portion of said sleeve and having a laterally projecting pin M' engaging a bifurcated member M² which is clamped to the shank I⁵ of the member I.

Admission of fluid to the hydraulic cylinder L is controlled by a valve N which is automatically reversed as the piston L² approaches the opposite ends of its movement by mechanism of the following construction.

Arranged parallel to the piston rod L³ is a rod O slideable in bearings O' and having secured thereto the collar O² which has spaced lugs O⁵ projecting laterally therefrom. N' is a rockable lever pivoted in a bearing N² in axial alignment with a rock shaft N³ which operates the valve N. The lever N' has a pin N⁴ extending into the path of the lugs O³ so that when the rod O is moved longitudinally one or the other of said lugs O³ will contact with the pin N⁴ to rock the lever N'. A spring N⁵ is attached to the lever N' and is so arranged that when the lever is moved to its mid-position in either direction the spring will quickly snap it the remaining distance. The lever N' is also connected to the rock shaft N³ by a lost motion connection comprising an eccentric pin N⁶ attached to the rock shaft engaging a cut-away portion N⁷ of the lever. Thus when the lever is actuated by the movement of the rod O it will first take up the lost motion between the lever and the rock shaft N³ and will then quickly rock said shaft by the actuation of the spring N⁵. The rod O is actuated by the piston rod L³ by means which as shown comprises a disk O¹ clamped between the sleeve J and the member M which extends between spaced lugs O⁶ on the rod O. The arrangement is such that the lost motion between the disk and the lugs O⁵ will permit the greater part of the travel of the piston L², but as said piston approaches the end of its movement towards either end of the cylinder it will contact with one or the other of the lugs O⁵ actuating the rod O and through the connecting mechanism just described reversing the valve N. The valve N is connected by conduits N⁸ and N⁹ to opposite ends of the cylinder L and the arrangement is such that in one position of said valve pressure fluid is admitted through the conduit N⁸ to one end of the cylinder, and an exhaust is also connected through the conduit N⁹ to the opposite end of the cylinder, while upon the reversal of the valve the pressure fluid is connected to the conduit N⁹ and the exhaust to the conduit N⁸. Consequently the function of the complete mechanism is to reciprocate the piston L² in the cylinder L, automatically reversing the movement after it reaches the ends of the cylinder.

With the mechanism as thus far described it

will be apparent that the work such as a spiral spur gear I³ carried by the member I will be simultaneously axially reciprocated and revolved in relation to the grinder wheel so as to produce a generating grinding of a tooth surface. Where the gear is provided with a series of teeth, it is necessary to rotatively index the work so as to produce corresponding developing grinding movements with respect to the successive teeth. This is accomplished by mechanism of the following construction.

80

The sleeve K' which surrounds the member I and pattern sleeve J has mounted thereon an index plate P having a series of peripheral V-shaped notches P' therein. P² is a V-shaped detent for engaging the notches P', this detent being mounted on a rock arm P³ pivoted at P⁴.

90

Adjacent and parallel to the index plate P is a member Q which has a hub portion Q' mounted

95

for rotation upon the sleeve K. It is also pro-

10

vided with a peripheral gear segment Q² which

105

is in mesh with a rack R formed on the central

110

portion of a double ended piston R' engaging a

115

cylinder R² which extends transversely of the

120

machine. The cylinder R² has adjustable stops

125

R³ at opposite ends thereof for exactly limiting

the travel of the piston so that when the piston

130

is reciprocated by fluid admitted alternately to

opposite ends thereof it will impart an oscillatory

movement to the gear segment Q² and the member Q bearing the same. The member Q is

135

further provided with a cam Q³ which engages

a roller P⁵ on the rock arm P³ to lift said rock

140

arm and thereby to disengage the detent P² from

the notch P'. Q⁴ is a pawl also carried by the

145

member Q which engages a ratchet ring P⁶ on

150

the side of the index plates P and during one

phase of the oscillatory movement will rotate

said plate an exactly predetermined amount.

Thus where fluid under pressure is alternately introduced at opposite ends of the cylinder R²

the piston R' will be reciprocated to oscillate the member Q, first disengaging the detent P² from

the index wheel by the operation of the cam Q³

engaging a roller P⁵ and also moving the pawl

Q⁴ to slip over the teeth of the ratchet ring P⁶

and then during the reverse oscillation moving

the index plate and finally locking the same by

re-engagement of the detent P².

It is necessary to effect this indexing during

125

the interval when the work has moved axially

out of engagement with the grinder wheel D

and before returning into engagement there-

with. This is accomplished and properly timed

by mechanism constructed as follows:

In alignment with the rod O is a valve casing

S containing a piston valve S' which has a stem

S² extending towards the rod O. The end of the

stem S² is partly cut away as indicated at S³

and the reduced portion engages a socket S⁴ at

135 the adjacent end of the rod O. Within this

socket is a rockable member S⁵ which in one

position will contact with the reduced end of

the member S² so as to move the same in an

axial direction. If, however, the member S⁵ is

rocked into a different position it will clear the

reduced end of the member S² so as to permit a

telescopic movement of said member with the

socket S⁴. A spring S⁶ within the cylinder S

actuates the piston in a direction counter to that

imparted by the rod O. S⁷ is a rock arm for rotat-

ing the member S⁵ being actuated in one direction

by a spring S⁸ and in the opposite direction by

engaging a stop S⁹ on the cylinder S. The ar-

angement of the parts is such that when the

rod O is moved in an outward direction by the disk O⁴ engaging the lug O⁵, the member S⁵ will bear against the reduced end of the stem S² and will actuate the valve S' against the tension of the spring S⁶. As soon, however, as the rock arm S⁷ engages the stop S⁹ the member S⁵ will be rocked to disengagement from the reduced end of the stem S² entering the cut away portion S³ whereupon the tension of the spring S⁶ will instantaneously return the valve S' to its normal position.

The valve S' controls a hydraulic motor comprising a cylinder T connected by a conduit T' with the valve casing S and containing a piston 15 T² which is actuated in one direction by the fluid entering through said conduit. A spring T³ in the cylinder T returns the piston T² to its normal position as soon as the valve S' has been returned, thereby connecting the conduit T' with 20 the exhaust. A rod T⁴ connected with the piston T² engages a rock arm U which rocks the stem U' of a valve U². This valve controls the cylinder R² being connected with the opposite ends thereof through the conduits U³ and U⁴, the construction being such that in the normal position of 25 the valve S' pressure fluid will be in the conduit U³ and the exhaust connected with the conduit U⁴, while in the reverse position of said valve S' the conduit U⁴ will be connected to the pressure fluid and the conduit U³ with the exhaust.

Complete operation

In the complete operation of the machine, the frame member G is first adjusted to the proper angle on the bed F corresponding to the helical angle of the gear to be ground and the work is then placed in engagement with the work holder I and adjusted into proper registration with the grinder wheel. This adjustment can be effected 35 by loosening one of the clamps M M² which permits rotation of the sleeve J with respect to the member I until proper registration is secured. The sleeve J is also selected to correspond to the particular gear. The trimming of the grinder 40 wheel is effected by the trimmer E with which the wheel is engaged by movement of the table B, but as this trimming mechanism forms no part of the present invention it will not be described in detail.

50 Movement is imparted to the work by the opening of the valve V which admits fluid under pressure to each of the valves N, S and U². The valve N will first admit pressure fluid to the outer end of the cylinder L through the conduit N³ and will connect the conduit N⁹ from the opposite end of said cylinder to the exhaust. This will move the piston L² forward carrying with it the member I which through its connection with the sleeve J and the engagement of helical grooves in the latter with the pins J' will be given a simultaneous axial and rotative movement, carrying the gear I³ past the grinder wheel D. Near the completion of this movement the disk O⁴ contacts with one of the lugs O⁵, thereby moving the rod O and through the lug O³ and pin N⁴ rocking the lever N' until the spring N⁶ completes the rocking movement with a snap. This will instantaneously reverse the valve N, admitting pressure fluid to the conduit N⁹ and connecting the conduit N³ with the exhaust, thereby reversing movement of the piston L². During this reverse movement the disk O⁴ contacting with the other of the lugs O⁵ will move the rod O outward, and as the rockable member S⁵ is in a position to contact with the reduced end of the stem S² the valve S' will

be actuated to admit fluid under pressure to the cylinder T. This will actuate the piston T² in said cylinder and through the rod T⁴ will rock the arm U and shaft U' of the valve U² so as to admit fluid under pressure into the conduit U³ to one end of the cylinder R² and to thereby move the piston R' in said cylinder. The time interval during which the valve S' admits pressure fluid to the cylinder T is very short, as the further movement of the rod O brings the rock arm S⁷ into contact with the stop S⁹, releasing the stem S² and permitting the stem S⁶ to quickly reverse the valve. Consequently the piston R' is also quickly reversed and the completion of the oscillatory movement of the member Q is within the short time interval that the work is out of engagement with the grinder wheel. As previously described in detail, the oscillation of the member Q effects indexing movement of the sleeve K' so that before the grinder re-engages with the work a 80 succeeding tooth is brought into operative relation thereto. This completes the cycle which is successively repeated until all of the teeth of the gear have been ground. The work then can be removed and a new blank engaged with the holder I and adjusted and then ground in a similar manner.

It will of course be understood that the grinder wheel is trimmed as frequently as necessary to maintain its proper cross sectional contour. This 105 can be done at any time by a movement of the table B which is effected by manually controlled means (not shown). It will be further understood that the contour to which the grinder wheel is trimmed is one which will develop the correct contour in the helical tooth, although not necessarily exactly the same in form. Thus due to the angle at which the grinder wheel is set relative to the axis of the gear or worm, the contact between the grinder wheel and the work will not be in the 110 axial plane of the grinder so that it is necessary to trim the wheel to a slightly different form from that which is developed in the tooth ground.

The use of hydraulic motors for actuating different parts of the mechanism has an additional 120 advantage that it does not interfere with the adjustment of the frame G to different angular positions corresponding to the helical angle of the work to be ground. Thus by the use of flexible conduits for the pressure and exhaust connections, the frame G can be readily adjusted without changing the operation of the hydraulic mechanism.

While I have specifically described a construction designed for the grinding of helical spur 130 gears in which the helical angle is such as to permit of actuating the work holder by axial pressure applied thereto, it is to be understood that my invention is applicable to the grinding of helical gears of all helical angles. However, where the 135 pitch of the helix is such as to lie within the angle of friction or pressures applied axially thereof, it is necessary to impart to the work holder a rotative movement. In Figure 11 such a construction is diagrammatically shown in which W 140 is the spindle for rotating the work W' and which has the helical pattern guide W² mounted thereon. W³ is a gear wheel on the spindle which is in mesh with a long driving gear W⁴. W⁵ is a stationary nut for engaging the helical pattern guide. 145 With this construction rotary movement is directly imparted to the spindle W by the long gear wheel W⁴ driving the gear wheel W³, while the pattern W² in cooperation with the stationary nut W⁵ causes the axial movement. The con- 150

struction is otherwise substantially the same as that previously described.

What I claim as my invention is:

1. In a machine for grinding spiral gears, the combination with a frame, a rotary arbor mounted thereon, a formed grinder wheel on said arbor, a table mounted on said frame to be pivotally adjustable about an axis perpendicular thereto intersecting the axis of said arbor and passing centrally through said formed grinder wheel, a work holder for the gear to be ground including a spindle capable of axial and rotary movements, an exchangeable sleeve surrounding and secured to said spindle and provided with a helical pattern guide, a surrounding bearing for supporting said spindle and sleeve mounted on said table, means for imparting to said spindle one of said movements and means cooperating with said helical pattern guide to produce in said spindle the other of said movements.
2. In a machine for grinding spiral gears, the combination with a frame, of a rotary arbor mounted thereon, a formed grinder wheel on said arbor, a table mounted on said frame to be pivotally adjustable about an axis perpendicular thereto intersecting the axis of said arbor and passing centrally through said formed grinder wheel, a work holder including a spindle capable of axial and rotary movements, an exchangeable sleeve surrounding and secured to said spindle and provided with a helical pattern guide, a surrounding bearing for supporting said pattern and sleeve mounted on said table, means for imparting to said spindle one of said movements, a member cooperating with said helical pattern guide to develop in said spindle the other of said movements, and means for indexing said cooperating member angularly about the axis of said spindle and helical pattern.
3. In a machine for grinding spiral gears, the combination with a frame, of a rotary arbor mounted thereon, a formed grinder wheel on said arbor, a table mounted on said frame to be pivotally adjustable about an axis perpendicular thereto, intersecting the axis of said arbor and passing centrally through said formed grinder wheel, a work holder for the gear to be ground, a bearing mounted on said table in which said work holder is supported permitting axial and rotative movement therein, an exchangeable pattern sleeved upon and secured to said work holder within said bearing and provided with one or more helical guides of a predetermined pitch, a member surrounding said pattern within said

bearing and engaging said helical guide, index mechanism for periodically rotatively adjusting the latter member and for locking the same in each position of adjustment and means operating when said member is locked for imparting to said work holder an axial movement whereby a helical movement corresponding to said pattern is developed therein.

4. In a machine for grinding spiral gears, the combination with a frame, of a rotary arbor mounted thereon, a formed grinder wheel on said arbor, a table mounted on said frame to be pivotally adjustable about an axis perpendicular thereto, intersecting the axis of said arbor and passing centrally through said formed grinder wheel, a work holder mounted on said table, an indexing mechanism therefor, reciprocating hydraulic motors for respectively actuating said work holder and index mechanism, valves controlling said motors, means operated by the reciprocation of said work holder for reversing the valve of the work reciprocating motor at opposite ends of the stroke thereof, and for double reversing the valve for the indexing motor at one end of said stroke whereby the index mechanism is quickly and completely actuated at one end of the work stroke.

5. In a machine for grinding spiral gears, the combination with a frame, of a rotary arbor mounted thereon, a formed grinder wheel on said arbor, a table mounted on said frame to be pivotally adjustable about an axis perpendicular thereto, intersecting the axis of said arbor and passing centrally through said formed grinder wheel, a work holder mounted on said table, an indexing mechanism therefor, reciprocating hydraulic motors for respectively actuating said work holder and indexing mechanism, valves for said motors, a valve actuated reciprocating rod, a lost motion connection between the reciprocating work holder and said valve actuating rod whereby the latter is actuated oppositely at opposite ends of the work stroke, means actuated by said valve rod for reversing the valve of the work reciprocating motor at opposite ends of its stroke, means also actuated by said valve rod for reversing the indexing mechanism motor at one end of the stroke of said rod, a spring for reversing the latter valve and a trip mechanism actuated at the completion of the stroke of said rod for releasing said latter valve to be reversed by said spring.

FREDERICK A. WARD.
